UNITED STATES PATENT OFFICE.

THOMAS A. ROBINSON, OF PATERSON, NEW JERSEY.

GAUZE-LOOM.

SPECIFICATION forming part of Letters Patent No. 671,148, dated April 2, 1901.

Application filed September 10, 1900. Serial No. 29,493. (No model.)

To all whom it may concern:

Be it known that I, THOMAS A. ROBINSON, a citizen of the United States, residing in Paterson, county of Passaic, and State of New Jersey, have invented certain new and useful Improvements in Gauze-Looms; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates to looms; and it has reference particularly to that class of looms which are employed for weaving gauze or other similar fabrics of the kind wherein is most commonly found that pattern of interlocked weave which is produced by carrying every alternate warp-thread over its neighbor first in one direction and then in the other, alternately with the forming of the sheds and the carrying of the weft-thread or filler therethrough.

The invention consists in the improved loom of the character above indicated and also in the combinations of its parts, constructed and arranged substantially as will be hereinafter particularly set forth and finally embodied in the clauses of the claim.

The invention is fully illustrated in the accompanying drawings, wherein—

Figure 1 is a side view of my improved loom. Fig. 2 is a top plan view, slightly enlarged, of that end portion of said loom which appears in Fig. 1. Fig. 3 is a vertical sectional view of said loom, taken just back of the harness and looking toward the front of the loom. Figs. 4 and 5 are enlarged detail views showing the batten and reed in section and also showing the mechanism whereby the sheds are formed in the body of the goods. Figs. 6 and 7 are plan views illustrating the mechanism whereby the weave is produced. Figs. 8 and 9 are respectively a side view and a sectional view, the latter being taken on the line xx of Fig. 8, of a certain traverse-motion mechanism; and Figs. 10 and 11 are views illustrating the manner of effecting the desired weave.

a designates the loom-frame, and b an auxiliary frame which extends from the rear end

of the loom and supports the rolls c , d , and e , the former one of which is for the selvage-warp, while the latter two are for the body-warp, the roll d carrying one half of said body-warp, (every alternate thread thereof,) while the roll c carries the remainder.

f denotes the take-up roll, disposed at the front of the loom in the ordinary manner and driven from the main shaft g by any suitable mechanism, and h is the batten carried by the fulcrumed lay-swords i , which are actuated from another shaft i' through pitmen j . On the batten is suitably arranged the reed k .

The shaft g carries two cams l , set to alternately raise two levers m , which are suitably fulcrumed in a convenient part of the loom-frame and to which are connected cords n , passing under pulleys o and in turn connected to a harness mechanism, which said levers are adapted to raise and lower and which comprise two sets of heddles p , heddle-levers q , cords r , extending downwardly from said heddles, around pulleys s to said levers q , and other cords t , extending upwardly from said heddles over pulleys u to the levers. This harness is adapted to control the selvage-warp, (marked v on the drawings,) which is thereby manipulated toward the production of the ordinary plain weave.

On the shaft g is mounted a cam v' of the shape substantially of the figure 8, and this cam controls a lever w , which is suitably fulcrumed in the frame and carries a roller x , bearing against the periphery of said cam.

On the back of the batten is arranged a pair of small brackets y , in which is pivoted a frame z , from which projects a series of needles 1, all disposed in a common plane. This series of needles is preferably as wide as the dent-space of the reed, exactly back of which it is disposed, the needles, furthermore, being situated in opposition to the spaces between the dents of said reed. From the frame z project two arms 2, connected to which are cords 3, which combine in a single cord 4 and then pass under pulleys 5 before being connected to the lever w . To said arms are likewise connected suitable springs 6, which are suspended from the arch of the loom-frame. These springs normally tend to maintain the series of needles horizontal, as shown in Fig. 4, and since when the needles are in this po-

sition and the filler *x* is bearing against one of the hollows of the periphery of the cam *v'* the cord connecting the frame *z* and the lever *w* is taut said lever will be constantly maintained in operative contact with said cam. In order that the needles may dip or turn into the substantially horizontal position far enough, the upper face of the batten, just back of the reed, is cut away, as shown in Figs. 4 and 5 at 7. A glass rod 8 is so arranged on the frame *z* as to be always uppermost whatever the position of said frame.

9 designates a reed which is arranged back of the harness, being suspended from the upper portion of the loom-frame by suitable cords 10, preferably made adjustable in any desired manner. Through this reed, as well as through the reed *k*, both selvage and body warp extend. Two threads, one from each body-warp roll, pass through each space of the reed *k* and through the corresponding space of the reed just referred to. One of these threads—*i. e.*, of the body-warp marked 12—extends through the eye of the corresponding needle of the series of needles 1, while the other—*i. e.*, of the body-warp marked 11—remains free. The rolls *d* and *e* and the glass rod 8 are so arranged that the warp 11 is just kept in contact with said glass rod by the reed 9, which is approximately alined with them at its top portion, while when the needles are raised to their vertical position the warp 12 will be elevated, (see Fig. 5,) a shed, which generates at the back from this reed 9, being thus formed.

Before being wound upon the take-up roll *f* the woven material extends over a traverse-roll 13. At one end this roll has a spindle 14, which rests on a grooved roller 15, mounted on the back of the breast-beam 16 of the loom, while at the other end of said roll is a trunnion 17, having a shoulder 18 and resting in a recess 19 of a block 20, there being a groove or depression 21 in the recess, which fits the shoulder of the trunnion. This block is carried at one end of a non-revolute spindle 22, which is arranged to reciprocate in a bracket 23, projecting from the breast-beam and to a pin or screw 24, extending from which is pivotally connected one end of a lever 25, also carried by said bracket, being fulcrumed on a pin 26, which projects therefrom. In arms 27, which extend downwardly from the bracket 23, is suitably journaled a sleeve 28, carrying a sprocket-wheel 28' and surrounded by a pair of parallel annular ribs 29, which are so shaped as to form a sinuous or cam-like way 31. In this camway runs a roller 32, which is carried at the lower end of the lever 25. The rotation of the sleeve obviously effects the reciprocation of the spindle 22, and consequently also of the traverse-roll, and said rotation is produced by a sprocket-chain 32', which passes over the sprocket-wheel 28' and also over another sprocket-wheel 33 on the main shaft. Between these two sprocket-wheels said chain

also passes under another wheel 34, journaled in a suitable bracket 35.

The filler is carried through the sheds by any suitable means, as the shuttle 34', which may be controlled in any desired manner.

In describing the operation of the loom attention is to be first called to the fact that the action of the cam *v'* is such that the needles 1 will be elevated every time the batten swings back, falling as it swings forward, and that the traverse of the roll 13 is a motion that is alternately to the right and back and to the left and back, starting from an intermediate position. The batten being back and the sheds being formed in the body as well as in the selvage warp by the needles and harness, respectively, the filler is carried therethrough. Thereupon the batten swings forward to beat up the filler, and as it does so the points of the needles drop into the space or recess 7 of the batten, depressing the rear portions of the threads 11 below the threads 12. The beating-up having been effected by the reed *k*, the roll 13 is traversed to either of its extremes of movement, which action, since the needle-points are disposed very close to the back of the reed and since the reed-spaces are somewhat wider than those of the ordinary reed, effects the carrying over of the threads 12 relatively to the threads 11. This carrying over of the threads 12 is brought about by virtue of the fact that their rear securing-points in the needles are quite near the forward securing means which the roller 13 affords and which is common to both sets of threads, whereas the securing-points of the threads 11—viz., in the reed 9—are considerably remote from said forward securing means. The threads being thus crossed, the batten again swings back, the needles at the same time rising, and the harness acting to form the sheds in the warp, both body and selvage. Thereupon the batten returns to again beat up the filler that has meantime been carried through the shed, the needles falling, and the roll, which assumed its intermediate position as the needles were raised, being ready to make the traverse to its other extreme of movement as soon as the beating up has been effected. In this manner the weaving progresses, the crossing of the threads 11 and 12 in the manner aforesaid occurring alternately with each carrying through of the filler.

In order that the roll may perfectly exert its influence on the warp as it traverses, said roll should be covered with baize or have its acting surface suitably adapted otherwise to the same end.

I do not wish to be limited to the exact structure nor to the precise combinations and arrangements of parts which have been hereinbefore particularly described; but

What I claim, and desire to secure by Letters Patent of the United States, is—

1. In a loom, the combination, with a frame, the threads of the warp being adapted to be maintained in two sets, of common means for

securing both sets of the warp-threads in one portion thereof, other means for securing said sets of threads in other portions thereof and separately, the one nearer to said common securing means than the other, means for moving the common securing means laterally with reference to the other, and alternately in each direction, one of said sets of threads being movable past the other and back again, in forming the sheds, in a direction substantially at right angles to, and at periods alternating with, the movements of said common securing means, and means for introducing the weft-thread or filler through the shed each time the same is produced, substantially as described.

2. In a loom, the combination, with a frame, and with means for advancing the warp, the threads of said warp being adapted to be maintained in two sets, of common means for securing both sets of threads in one portion thereof, said means being laterally movable, separate means for securing each set of threads in another portion thereof, the one appreciably farther from the movable securing means than the other, means for moving said movable securing means alternately in each direction, means, also, for moving one of the separate securing means past the other and back again, in forming the sheds, in a direction substantially at right angles to, and at periods alternating with, the lateral movements of said common securing means, and means for introducing the weft-thread or filler through the shed each time the same is produced, substantially as described.

3. In a loom, the combination, with the frame and with means for advancing the warp, the threads of said warp being adapted to be maintained in two sets, of common means for securing both sets of threads in one portion thereof, said means being laterally movable, means for moving one set of threads vertically past the other and back again alternately with the lateral movements of said common securing means, thus forming the sheds, and means for introducing the weft-thread or filler through the shed each time the same is produced, substantially as described.

4. In a loom, the combination, with the frame and with means for advancing the warp, the threads of said warp being adapted to be maintained in two sets, of a laterally movable roll engaging in common both sets of threads in one portion thereof, a series of pivoted needles engaging one set of threads in another portion thereof, means for moving said roll alternately in each direction, said roll and the axis of the needles being substantially parallel, means, also, for oscillating said series of needles to move the set of threads held thereby past the other and back again, at periods alternating with the lateral movements of said roll, and means for intro-

ducing the weft-thread or filler through the shed each time the same is produced, substantially as described.

5. In a loom, the combination, with a frame, and with means for advancing the warp, the threads of said warp being adapted to be maintained in two sets, of a laterally-movable roll engaging in common both sets of threads in one portion thereof, a reed and a series of pivoted needles respectively engaging said sets of threads in another portion of each of them and the one being appreciably farther from the roll than the other, means for moving said roll alternately in each direction, said roll and the axis of the needles being substantially parallel, means, also, for oscillating said series of needles to move one set of threads past the other and back again, at periods alternating with the lateral movements of said roll, and means for introducing the weft-thread or filler through the shed each time the same is produced, substantially as described.

6. In a loom, the combination, with a frame, take-up and let-off means, a batten and batten-actuating means and a reed mounted on said batten, of a laterally-movable roll engaging in common both sets of threads in one portion thereof, a reed and a series of needles respectively engaging said sets of threads in another portion of each of them and the one being farther than the other from the roll, means for moving said roll alternately in each direction, said series of needles being pivoted on the batten and having its axis of movement substantially parallel with said roll, means, also, for oscillating said series of needles to move one set of threads past the other and back again, at periods alternating with the lateral movements of said roll, and means for introducing the weft-thread or filler each time the shed is produced, substantially as described.

7. In a loom, the combination, with a frame and with means for advancing the warp, the threads of said warp being adapted to be maintained in two sets, of means, engaging corresponding portions of said sets of threads, for moving them together laterally, means for securing one set of threads in another portion thereof against movement, means for moving one set of threads vertically past the other and back again alternately with the lateral movements of said sets of threads in their corresponding portions, thus forming the sheds, and means for introducing the weft-thread or filler through the shed each time the same is produced, substantially as described.

In testimony that I claim the foregoing I have hereunto set my hand this 25th day of August, 1900.

THOMAS A. ROBINSON.
